CLAIM

The ornamental design for a carrying device for babies, as shown and described.

DESCRIPTION

1.1 is a perspective view of a carrying device for babies in accordance with the present invention;

1.2 is a front view of the carrying device for babies of **1.1**;

1.3 is a rear view of the carrying device for babies of **1.1**;

1.4 is a side view of a first side of the carrying device for babies of **1.1**;

1.5 is a side view of a second side of the carrying device for babies of **1.1**;

1.6 is a bottom plan view of the carrying device for babies of **1.1**; and

1.7 is a top plan view of the carrying device for babies of **1.1**.

In the drawings, the broken lines represent portions of the carrying device for babies that form no part of the claimed design.
